UNITED STATES PATENT OFFICE.

LOUIS E. ISELE, OF NEWARK, NEW JERSEY.

TOY.

Application filed March 17, 1921. Serial No. 453,080.

To all whom it may concern:

Be it known that I, LOUIS E. ISELE, a citizen of the United States, residing at Newark, in the county of Essex and State 5 of New Jersey, have invented a new and useful Improvement in Toys; and I do hereby declare the following, when taken in connection with the accompanying drawings and the characters of reference marked 10 thereon, to be a full, clear, and exact description of the same, and which said drawings constitute part of this application, and represent, in—

Fig. 1 a side view, partly in section, of a 15 toy constructed in accordance with my invention.

Fig. 2 a front view of the same.

Fig. 3 a top or plan view of the same.

Fig. 4 a perspective view of the sprocket- 20 wheel detached.

Fig. 5 a perspective view of the pulley detached.

Fig. 6 a sectional view through one of the buckets, showing the means for attaching 25 the same to the chain.

My invention relates to improvement in toys, and particularly to toys used by children in playing with sand, the object being to provide a toy simulating a bucket-con- 30 veyor which is simple in construction and, therefore, cheap to manufacture, and adapted to afford amusement to children, and the invention consists in the construction and arrangement of parts as will be hereinafter 35 described and particularly recited in the claims.

Superimposed upon a base 10, struck up from sheet-metal with an upstanding flange 11, is a pocket 12, also struck up from sheet- 40 metal, and mounted at the upper end of the pocket is a hopper 13 discharging into the pocket. Secured to the sides of the pocket, and projecting upwardly and forwardly therefrom, are side-bars 14 and 15, being 45 connected together at their outer ends by a bar 16, which is preferably formed integral with the side-bars 14 and 15. These side-bars are connected together by a transverse-brace 17, which in turn is supported by up- 50 rights 18 and 19, which are secured at their lower ends to the flange 11. The hopper 13 is also supported from the transverse-brace 17 by stay 20, the stay, uprights and side-bars being formed from wire. Mounted on 55 the bar 16 is a pulley 21, and on a crank-shaft 22, mounted in the sides of the pocket

12, is a sprocket 23, and extending over the sprocket 23 and around the pulley 21 is a chain 24, to which buckets 25 are attached. The pulley 21 is formed from two disks of 60 metal 26 offset at the center and formed in their edges with radially-projecting flanges 27. These disks are brought together and secured so as to form a space between the flanges 27 for the passage of the chain 24, 65 while the sprocket 23 is formed from two similar disks except that the flanges are notched to form teeth 32 and the disks are reversed in position, so that the teeth of the two disks register and so as to form 70 sprocket-teeth to engage with the chain 24 and move that chain under the action of the crank-shaft 22, which is provided with a crank-handle 28. The sprocket and pulley may be located on their respective shafts by 75 upsetting the metal of the shaft on opposite sides. The buckets 25 are attached to the chain by forming them with perforations 29, through which eyes 30 of the chain may extend and through which eyes pins 31 may be passed, so as to interlock the buckets with 80 the chain. These buckets are arranged at intervals and the pocket filled with sand, which may be supplied through the hopper 85 13. As the crank is turned the buckets are brought down beneath the sprocket 23 and into the mass of sand in the pocket, so as to 90 pick up a portion of the sand, which is carried upward and forward by the chain, over the pulley 21, at which point the bucket is 95 reversed in position, so as to discharge its load.

This construction provides an attractive toy, simple to manufacture and not liable to become disarranged, and capable of affording amusement to children playing in sand.

I claim:

1. A toy of the class described including a sprocket-wheel, a pulley and a chain extending around the same, buckets secured to said chain, said sprocket and pulley formed from disks of metal having inwardly offset centers and radial teeth.

2. A toy of the class described including a sprocket-wheel, a pulley and a chain extending around the same, buckets secured to said chain, said buckets formed with openings adapted to receive the eyes of the chain, and pins extending through said eyes, whereby the buckets are interlocked with the chain.

3. A toy of the class described comprising

a base, a pocket mounted thereon, a hopper discharging into said pocket, bars secured to opposite sides of the said pocket and projecting upwardly and outwardly therefrom, and connected together at their outer ends, a pulley mounted between said side-bars at their outer ends, a crank-shaft mounted between the walls of said pocket, a sprocket-wheel on said shaft, a chain extending around said sprocket wheel and pulley,

buckets secured to said chain, braces supporting said side-bars, and a stay supporting the upper edge of said hopper.

In testimony whereof, I have signed this specification in the presence of two subscribing witnesses.

LOUIS E. ISELE.

Witnesses:

LOUIS LARSEN,
CHARLES LARSEN.
